PRESS FOR PRINTING INDIVIDUAL WORK-
PIECES SUCH AS ENVELOPESRoss E. Skow, Kansas City, Mo., assignor to Wal-
bert Machine Company, Kansas City, Mo., a
corporation of Missouri

Application May 19, 1950, Serial No. 162,909

16 Claims. (Cl. 101—232)

1

This invention relates to a press for printing individual work pieces, such as envelopes, to a customer's order.

For example, printers and envelope manufacturers have many customers requiring envelopes printed to their specifications, but with present day high production machines it is economically impracticable to set them up for small quantity runs. On the other hand, standard stock sizes of envelopes may be manufactured on such machines at relatively low cost, but the envelopes then require printing for the customer's needs.

It is, therefore, the principal object of the present invention to provide a relatively small printing press that may be easily set up to print economically, envelopes in accordance with a customer's requirements. In this way, printed envelopes may be supplied to the customers at substantially low cost because of the economic manufacture of envelopes by present day, high production, envelope manufacturing machines.

Other objects of the invention are to provide a printing press of this character with a simple and positive feeding mechanism whereby envelopes may be individually fed from a stack and kept in continuous high speed movement in spaced sequence while being delivered to the printing mechanism; to provide means for retaining a positive grip on the envelopes while they are passed between the printing plate cylinder and the impression cylinder of the printing mechanism, thereby eliminating smearing of the ink; to provide for registration of the envelopes in both the direction of travel and in a side wise direction thereby assuring accurate placement of the printing; to provide the printing press with a safety mechanism for automatically stopping operation of the press in case of pile-ups or misfeed of the envelopes; and to provide means for indicating when a given number of envelopes have passed through the printing press thereby facilitating placement of the given number of envelopes in a package or container.

It is also an object of the invention to provide a printing press adapted to print many types of envelopes, jackets, folders and the like, either on the face or back sides. Other objects of the invention are to provide the press with a feeding mechanism that is not dependent upon engagement of the flap of the envelopes; to provide a press adapted to feed and print any weight of envelopes, from light weight air mail to 32 substance or heavier stock; and to provide a printing press and feed therefor which operates successfully on envelopes that have become warped during manufacture or storage.

2

A further object of the invention is to maintain working mechanisms of the press in synchronism by means of a common drive.

In accomplishing these and other objects of the invention as hereinafter pointed out, I have provided an improved structure the preferred form of which is illustrated in the accompanying drawings, wherein:

Fig. 1 is a perspective view of a printing press constructed in accordance with the present invention.

Fig. 2 is an enlarged side view of the main portion of the press, portions being broken away for better illustration.

Fig. 3 is a longitudinal section through the main portion of the press.

Fig. 4 is a plan view of the main portion of the press.

Fig. 5 is a rear elevational view of the printing press.

Fig. 6 is an underneath perspective view of the discharge table of the press particularly illustrating the counting mechanism for indicating when a given number of envelopes have been printed.

Fig. 7 is an enlarged view of the timing switch for the count indicating arm.

Fig. 8 is a longitudinal section through the withdrawal cylinder particularly illustrating the vacuum nozzles for engaging the individual envelopes and the valve member for controlling the suction through the nozzles.

Fig. 9 is a section through the valving member on the line 9—9, Fig. 8.

Fig. 10 is a fragmentary perspective view of the adjustor for timing arrival of the envelopes relatively to the printing plate cylinder.

Referring more in detail to the drawings:

1 designates a printing press constructed in accordance with the present invention and which includes a casing-like base 2 forming a closure for an operating motor 3, countershafts 4, 5, and 6, and the driving connections therebetween. The countershaft 4 constitutes the main drive and is provided with a pulley 7 operated from a pulley 8 on the armature shaft 9 of the motor by means of a belt 10. The shafts 5 and 6 constitute drives to operating mechanisms of the printing section of the press generally indicated at 11. The printing section includes a series of inking and ink transfer rollers 12, a printing plate cylinder 13 adapted to receive the printing plate, and an impression cylinder 14 that is movable to and from the printing plate cylinder 13 as later described. The shaft 5 is operated from the shaft 4 through pulleys 15 and 16 fixed to

the respective shafts and interconnected by an endless belt 17. The shaft 6 is driven from the shaft 5 through a chain and sprocket connection as indicated at 18. The various rollers of the printing section of the press are mounted in side frames 19 carried upon the forward portion of the base 2.

Also carried on the base 2 rearwardly of the printing section are laterally spaced plate-like standards 20 and 21 that are interconnected at their upper ends by a cross bar 22. Also connecting the upper ends of the standards 20 and 21 at a slightly lower level relatively to the cross bar 22 is a yoke shaped frame 23 having side arms 24 and 25 provided with outwardly offset portions 26 and 27 by which the yoke shaped frame is connected with the standards through fastening devices 28. The opposite ends of the arms 24 and 25 are connected by a cross bar portion 29 of the yoke.

The frame 23 cooperates with a withdrawal cylinder 30 to support a stack of envelopes 31 as best shown in Fig. 2. The stack of envelopes 31 is retained in a vertical position by posts 32—33 and 34—35, each being supported by a slotted foot 36 attached to the lower end thereof. The foot portions 36 of the respective posts 32 and 33 are carried on lugs 37 projecting inwardly from the cross bar 29, and the foot portions 36 for the posts 34 and 35 are carried on similar lugs 38 projecting inwardly from the side arms 24 and 25 of the yoke shaped frame. When thus mounted, the posts 32 and 33 engage the rear of the stack and the posts 34 and 35 engage the sides of the stack. The foot portions 36 are adjustably secured to the lugs 37 and 38 by cap screws 39 that extend through the slots and into threaded openings of the lugs. The front portion of the stack is backed by vertical members 40 and 41 carried on the cross bar 22 by angle shaped brackets 42. The brackets are attached to the rear faces of the members 40 and 41 and they have arms 43 provided with slots 44 adjustably anchored to the cross bar 22 by fastening devices 45 whereby the vertical members 40 and 41 may be adjusted to cooperate with the posts in retaining the front edges of the envelopes substantially in a vertical plane with the axis of the withdrawal cylinder 30.

The withdrawal cylinder 30 constitutes a cylindrical body 46 which may be of less length than the transverse dimensions of the envelopes and which is provided near the ends thereof with annular grooves 47 and 48 for a purpose later described.

Formed in the withdrawal cylinder at opposite diametrical sides thereof are laterally spaced suction ports 49—50 and 51—52, the ports in the respective sides of the cylinder being interconnected by manifold channels 54 and 55 which open inwardly from a recess 56 at one end of the cylinder as best shown in Figs. 8 and 9. Extending axially through the cylinder is a shaft 57 having projecting ends 58 and 59 journaled in suitable bearings 60 of the standards 20 and 21 as shown in Fig. 5.

Mounted within the recess 56 is a valving disc 61 having an axial opening 62 therein for passing the shaft 57. The disc 61 has a valving face 63 that is retained in contact with a corresponding face 64 formed by the bottom of the recess 56, the valve disc being retained by a collar 65 that is fixed to the shaft 57, as best shown in Fig. 8. The valve disc 61 is retained from rotation by an arm 66 fixed to the cross bar 29 and

having an end 67 thereof secured to the periphery of the valve disc by fastening devices such as screws 68 as shown in Fig. 2. Formed in the face 63 of the valve disc is an arcuate channel 69 that is adapted to successively register with the manifold channels 54 and 55 incidental to rotation of the withdrawal cylinder so as to establish suction through the respective pairs of nozzles whenever the arcuate channel is registering with the inlets of the manifold channels.

In order to establish suction through the nozzles the valve disc 61 carries a nipple 70 that is in connection with the arcuate channel as shown in Figs. 8 and 9. The nipple projects from the outer face of the valve disc and is connected with a flexible duct or hose 71 leading to a vacuum pump (not shown) which may be housed within the base 2 of the machine or connected with any suitable vacuum line usually available in an envelope manufacturing establishment.

As above stated, the stack of envelopes is partially carried by the frame 23. This is effected by providing the foot portions of the posts 32 and 33 with tongues 72 and 73 that are secured to the posts by clamps 74 and 75 so as to engage under the rear edge of the stack as shown in Fig. 2 while the front portion is bearing upon the withdrawal cylinder and in position to be engaged by the nozzles. The envelopes, when engaged by the cylinder, are carried downwardly and forwardly through an arcuate pass 76 that is formed between the peripheral face of the cylinder on one side and a plurality of arcuate bars 77 that are spaced apart along the length of the cylinder and which are adjustably carried on the cross bar 78 that is carried by arms 79 pivotally attached to the transverse bar 22 previously described as indicated at 80 (see Fig. 2).

To facilitate control of downward feed of the envelope, from the stack and hold back the envelopes while an envelope is being withdrawn by the withdrawal cylinder, the cross bar 22 carries an angle shaped bracket 81 for attaching a vertical control member 82 having a rubber facing 83 in contact with the edges of the envelopes as shown in Fig. 3. The bracket 81 has a slotted foot portion 84 that is mounted on the bar 22 by a fastening device 84'. The bracket 81 carries a member 85 having laterally directed ears 86 and 87 for rotatably supporting an adjusting screw 88 that is threadably engaged with a lug 89 projecting from the member 82 as shown in Fig. 3 and seating a spring 89' that is on the adjusting screw 88 and bears against the lug 89. The upper end of the adjusting screw has a knurled head 90 by which it may be rotated to raise and lower the member 82 and adjust the lower end relatively to the peripheral face of the withdrawal cylinder. The lower end 91 of the resilient facing 83 depends from the lower end of the member 82 so as to provide a flexible lip 92 bearing on the withdrawal cylinder and under which the first or lowermost envelope is adapted to move while the resilient facing assists in holding back the remaining envelopes in the stack.

To relieve the weight of the upper envelopes in the stack from the lower envelopes, the bar 29 of the yoke frame carries an angle bracket 94 adjustably mounting a reversely arranged bracket 96 having a slotted foot 97 to pass a retaining screw 98 whereby when the screw is loosened the bracket 96 may be shifted to and from the stack. Carried by a vertical arm 99 of the bracket 96 is a downwardly and outwardly projecting terminal

(100) supporting a finger (101) that is adapted to engage and support the upper portion of the stack in cooperation with the resilient facing (83). The lower envelopes which are the first removed, are therefore more freely removed by the withdrawal cylinder. To facilitate seal about the suction nozzles, the ports may be counterbored and faced with resilient bushings (102) as shown in Fig. 8. These bushings project slightly from the surface of the withdrawal cylinder to effect a seal with the envelope being withdrawn and since they are subject to wear they are supported on threaded bushings (103) that are threaded into the cylinder. The threaded bushings are adapted to be turned by a tool (not shown) which is inserted through the rubber bushings and engaged within hexagon shaped bores (103') of the threaded bushings.

The withdrawal cylinder is rotated from the countershaft (4) by means of a chain belt (104) operating over a sprocket (106) fixed to the countershaft (4) and a sprocket (105) fixed to the cylinder shaft (57). The withdrawal cylinder carries the envelopes from the bottom of the stack and deposits them upon a conveyer which carries them to the printing section of the press as now to be described.

Extending parallel with the axis of the withdrawal cylinder and at a point therebelow is a shaft (107) carrying laterally spaced sprockets (108) and (109) which substantially register with the annular grooves of the withdrawal cylinder. Journalled in the side frames (19) in substantially the same horizontal plane as the shaft (107) is a shaft (112) also mounting sprockets (113) and (114) registering with the sprockets (108) and (109) for carrying endless chain belts (115) and (116) having upper runs (117) operating in channel tracks or rails (118) and (119), the upper side edges (120) and (121) of which are located slightly above the level of the upper runs of the chains (117) and sufficiently below the under surface of the withdrawal cylinder to allow the envelopes to pass therebetween and to be moved into position for engagement of the envelopes by pins (122) that are spaced along the length of the respective chain belts to move the envelopes into the printing section of the press.

The ends of the side rails of the channel tracks may be suitably shaped. For example, the ends extending under the withdrawal cylinder may be curved downwardly as indicated at (123) while the opposite ends may have the undersides tapered as at (124) to permit the ends thereof to project in close relation with the path between the printing plate cylinder and the impression cylinder of the press. The tracks or rails (118) and (119) are carried by a cross bar (125) having its ends secured to longitudinal rails (126) and (127) that connect the vertical plates of the frame at the respective sides of the press with the side frames (19).

Also carried by the cross bar (125) are angle shaped side guides (128) and (129) for guiding the ends of the envelopes and assuring transverse registry of the envelopes with the printing plate cylinder while they are being moved into printing position. The side guides (128) and (129) are carried on angle shaped brackets (130) that are adjustable on the bar (125) as best shown in Fig. 4. One of the side guides is positioned parallel with the conveyor chains to serve as a fixed stop for the side edges of the envelopes moving therewith. The other guide however is set at an angle thereto with the delivery end spaced from the

delivery end of the other guide a distance substantially corresponding with the sidewise width of the envelopes. The opposite end of the guide is spaced a greater distance to assure free entrance of the envelopes therebetween. With this arrangement of the guides the envelopes are caused to move transversely while they are being carried to the printing section of the press. When the envelopes reach the restricted end of the guides, they are in sidewise registry with the printing position.

Projecting rearwardly from the cross bar (125) at a point midway between the conveyor tracks (118) and (119) is a tongue (131) pivotally mounting bell crank levers (132) and (133) with arms (134) thereof projecting alongside the channel shaped tracks or rails and carrying pressure or transfer wheels (135) that cooperate with the withdrawal cylinder (30) in directing the envelopes onto the edges (120) and (121) of the rails (118) and (119). The pressure wheels (135) are retained in contact by springs (136) connected with the other arms (137) of the bell crank levers and with a fixed part of the frame (Fig. 3).

The conveyor pins (122) are carried on plates (138) that are adjustably mounted on lugs (139) that project laterally from the outsides of selected links of the chain belts (115) and (116) and move along the inner sides of the outer edges of the tracks or rails as best shown in Figs. 2 and 4.

30. The conveyor belts (115) and (116) are operated from the countershaft (4) through a countershaft (140) having a sprocket (141) thereon aligning with a driving sprocket (142) on the countershaft (4), the sprockets (142) and (141) being connected in driving relation by an endless chain belt (143). The shaft (112) projects outwardly from the side of the machine and carries a sprocket (144) that is adjustably positioned on the shaft by a collar (145) whereby the sprocket (144) may be advanced or 40. shifted retractably relatively to the shaft (112) so as to adjustably position arrival of the envelopes relatively to the printing roller (13). This is effected by providing a loose fit of the hub (148) of the sprocket (144) on the shaft (112) and providing the adjacent end of the collar (145) with a recess (147) to receive the adjacent end of the hub (148). The collar (145) is affixed relatively to the hub (148) by a set screw (148') that is threaded into the hub (148). The collar is adjustably retained on the shaft (112) by a set screw (149) threaded into the collar and having an end bearing on the shaft (112), as best shown in Fig. 10.

When it is desired to advance the sprocket (144), the setscrew (148') may be loosened and the collar turned to position the sprocket after which the setscrew is retightened. To facilitate turning of the collar, the periphery thereof may be provided with knurling as indicated at (150). The sprocket (144) is driven from the shaft (140) by means of a chain (151) operating over a sprocket (152) on the outer end of the shaft (140), and over a sprocket (153) that is mounted on the outer end of the printing roller shaft (154). The sprocket (144) engages the upper run of the belt as best shown in Fig. 2, and is driven thereby. In this manner the withdrawal cylinder, feed conveyor, and the printing plate cylinder are all kept in timed relation so as to maintain control of the envelopes and deliver them in proper registry to be printed thereon.

The envelopes are kept in contact with the longitudinal guide rails by longitudinal top guides or rods (155) carried at their respective ends on crossbars (156) and (157) of a frame (158). The frame

158 also includes side arms 159 and 160 having outwardly offset ends 161 which are pivotally engaged within the vertical plates 20 and 21 by cap screws 162 as shown in Figs. 4 and 5. The rods 155 are carried by C-clamps 163 fixed to the upper sides of the rods 155 and have notched-like seats 164 receiving the crossbars 156 and 157 as best shown in Fig. 2. The C-clamps are kept in adjusted position on the crossbars by setscrews 165. The rear ends of the rods or those adjacent the withdrawal cylinder 45 are curved upwardly as indicated at 166 to facilitate the entrance of the envelopes thereunder. In case of pile-up of the envelopes under the frame, the frame 158 may be raised on the pivotal connections 162 thereof with the plates 20 and 21 and the envelopes may then be readily removed.

To automatically stop the machine in case of pile-up of two or more envelopes between the withdrawal cylinder and the printing unit, I provide a central rod 167 having vertical stems 168 and 169 near the respective ends thereof that are slidable within vertical openings in a longitudinal bar 170. The bar 170 has yoke shaped ends 171 and 172 engaging the crossbars 156 and 157, as shown in Fig. 3, and which are clamped thereto by setscrews 173 and 174. The stems 168 and 169 are free sliding in the supporting bar 173 so that the rod 167 rides freely upon the envelopes as they are moved thereunder, but when two or more envelopes pile up, the bar raises and operates a switch 175 that is mounted on the supporting bar 170 and which is adapted to be actuated by a strap 176 connecting the upper ends of the stems 168 and 169, the plate 176 being anchored to the stems by jam nuts 177 and 178 engaging the respective sides of the plate. The plate is adapted to operate an arm 179 of the switch through a pivotal connection 180. The switch 175 is connected in the circuit of the motor 3. Therefore, should two or more envelopes begin to bunch up on the conveyor, the switch 175 is automatically operated to stop operation of the machine.

There may be times when an envelope should fail to be withdrawn by the withdrawal cylinder so that a space would occur on the feed conveyor. Therefore, the printing plate cylinder would apply ink on the impression cylinder of the printing press with the result that the next succeeding envelope would be printed with an offset on the under side thereof by the ink deposited on the impression cylinder. To avoid this difficulty, means is provided for shifting the impression cylinder from contact with the printing plate cylinder as now to be described. Carried by a suitable insulated bracket 182 on the longitudinal bar 170 is a contact arm 183 that rides along the upper face of the envelopes and if an envelope is absent to make contact with a ground contact 184 that is carried by the crossbar 125. The housing 185 in Fig. 3 indicates a solenoid magnet connected with a current supply on one side and with a switch 186 that is operated by a cam 187 on the shaft 107 so that when an envelope should be passing under the contact arm 183 the switch 186 is closed to effect flow of current to the solenoid by way of the contact arm 183 and ground contact 184 in the absence of an envelope. The solenoid magnet includes an operating arm 191 that is connected with an arm 192 on a rockshaft 193. Mounted on the rockshaft 193 is a latch 194 that engages in a notch 195 of a pin 196 which extends laterally from an arm 197. The arm 197 is carried on a shaft 198 extending transversely

under the impression cylinder and which has eccentrics 199 on the ends thereof. Mounted on the eccentrics are eccentric straps 200 that are pivotally connected with slide blocks 201 that rotatably carry the impression cylinder. When the solenoid is energized and the latch 194 is disengaged relatively to the arm 197 the weight of the impression cylinder supplemented by a spring 202 (Fig. 2) causes the eccentrics to rock and drop the impression cylinder out of contact by the printing plate cylinder. The impression cylinder is reset by an operating lever 205 connected with the shaft 198, as shown in Fig. 2.

In order to adjust the arm 197 relatively to the shaft 198, the arm is loose on the shaft but is connected therewith through a fixed arm 206 pivotally carrying an internally threaded sleeve 207 which mounts an adjusting screw 208, the adjusting screw being rotatably connected with the arm 197 as shown in Fig. 3.

To assure that the envelopes are contacted by the pins on the feed chains, the envelopes are engaged by a brush 211 that is carried by the crossbar 157 and which is adapted to press on the envelopes and retard movement thereof until the pins make contact with the rear edges of the envelopes. When the envelopes are carried up to the printing plate cylinder they are engaged between upper and lower feeding rollers 209 and 210 that are driven in synchronism with the printing plate and impression cylinders. This is effected by interconnecting the rollers 209 and 210 by gears 212 and 212' with the gear 212 meshing with an idler gear 213 which in turn meshes with a gear 214 on the impression cylinder shaft as shown in Fig. 3. The ratio of the gears is such that the peripheral speed of the feed rollers correspond with the face speed of the impression cylinder and with the face speed of the printing plate that is attached to the surface of the printing plate cylinder. Attention is here directed to the requirement that the envelopes when engaged between the feed rollers must be moved thereby at a higher speed than the speed of the conveyor chains, otherwise, the conveyor pins would not clear the envelopes, as the pins are carried around the sprockets 113 and 114. The upper feed roller is preferably in the form of a lateral series of spaced contact rollers as shown in Fig. 4 to leave spaces therebetween to accommodate guides 215 that are carried from a crossbar 216 of the printing frame. The guides serve to hold the envelopes down and in plane with the path between the printing plate and impression cylinders, thereby assuring their entrance therein. The feed rollers are so located with respect to the printing plate and impression cylinders that they retain gripping contact with an envelope even while the envelope is passing the printing plate cylinder and is being printed thereby. In fact, the contact is maintained until the forward edge of the envelope has passed the printing plate cylinder and is gripped by rollers 217 which bear upon the impression cylinder. The rollers 217 are carried on arms 218 that are mounted on a cross shaft 219 (Fig. 3). Thus the envelope is positively held while it is being printed, the rear gripping rollers retaining hold of the envelopes until the front rollers have engaged therewith.

After passing of the envelopes through the printing unit they are discharged on a conveyor table 220 that is adjustably carried relatively to the printing unit by links 221 pivotally connected with ears 222 projecting forwardly from the frame of the printing unit and which have their

opposite ends pivotally connected with depending ears 223 on the frame of the discharge table, the links carrying screws 224 adjustably engaging against the bottom of the table (Fig. 3). The opposite end of the table is carried on supporting legs 225 having rollers 226 on which that end of the table rocks when making the adjustment (Fig. 1).

Carried beneath the table 220 at the respective ends thereof are countershafts 228 and 229. Mounted on the countershafts are laterally spaced pulleys 230-231 and 232-233. Operating over the pulleys are endless belts or webs 234 and 235 with the upper runs 236 and 237 thereof moving along the upper surface of the table, as best shown in Fig. 1, to carry the printed envelopes along the length of the table and into position for removal and placement into the boxes in which they are packed. Pressure wheels 238 and 239 are carried on arms 240 which are pivotally connected as at 241 to arms 242 that are fixed to a cross shaft 243 as best shown in Figs. 3 and 4, the cross shaft being supported at its ends in clamping brackets 244 to maintain a fixed angular position of the arms 242 whereby the position of the wheels are adjusted to and from the printing rollers. If desired, a resilient tongue 245 may be provided to bear upon the envelopes intermediate the pressure wheels, the tongue 245 being carried by the shaft.

In order to indicate when a given number of envelopes have passed through the printing section of the press, means is provided to shift the last envelope in the group out of alignment with respect to the rest of the envelopes. This is effected by a shift arm 246 located at one side of the table and carried by a vertical shaft 247 which is pivotally mounted therein and adapted to be operated by an arm 248. Actuated in timed relation with the feeding conveyor and adapted to make one revolution with the passage of a given number of envelopes through the printing unit is a shaft 249 rotatably supported under the frame 250 of the delivery table. Fixed to the shaft 249 is a sprocket 251 that is driven by a belt 252 from a sprocket 253 of a speed reduction mechanism indicated by the housing 254 in Fig. 3. The speed reduction mechanism is actuated from the countershaft 112 by a chain belt 255 operating over a sprocket 256 on the shaft 112, also best shown in Fig. 3. The shaft 249 carries a cam disc 258 having a dwell 259 therein adapted to engage a roller 260 on an actuating arm 261 of a switch 267. The switch 267 is connected in circuit with an electromagnet 268 that is mounted on the underside of the delivery table and is connected by a link 269 with the arm 248, so that when the dwell 259 of the cam disc 258 engages the roller 260, the switch 267 will be actuated to energize the electromagnet 268. Energization of the magnet swings the arm 248 and rocks the shaft 247 for swinging the shift arm 246 inwardly against the envelope then moving in flight onto the conveyor belts to shift that envelope out of line and indicate that a given number of envelopes have passed through the printing unit. A stop 271 is provided on the table opposite the shift arm 246 to limit displacement of the envelopes, the stop 271 being adjustable to the length of the envelope by providing the supporting arm 272 thereof with a slot 273 through which a fastening device such as a screw 274 is inserted into the table 220. The switch 267 is adjustable relatively to the cam disc 258 by mounting of the switch on an arm 276 that swings about the axis of the 75

shaft 249 and which is retained in an adjusted position by clamping the arm 276 to a bracket 277 which depends from the under side of the table. The clamp is effected by a screw 278 which is carried by the arm 276 and passes through an arcuate slot 279 in the bracket 277.

Ordinarily the operator will have removed the printed envelopes from the belts before they reach the end of the table. However, to stop the envelopes the table may be provided with upwardly inclined rests 280 as indicated in Fig. 1.

The table conveyor belts are driven from the shaft 249 by a chain 281 operating over a sprocket 282 on the shaft 249 and a sprocket 284 on the shaft 228. The belts 234 and 235 may be adjusted by mounting the shaft 228 on brackets 285 that are adjustably attached to the frame of the table by bolts 286 that extend through slots 287 in the brackets as shown in Fig. 6.

20 The chains of the feed conveyor are kept in proper tension by sprockets 288 and 289 engaging the respective chains 115 and 116. The sprockets are carried on arms 290 fixed to a rockshaft 291 which is pivotally mounted in the frame of 25 the press. The sprockets are yieldingly retained in contact with the chains by springs 292 connected with the arms 290 and a fixed part of the frame. The withdrawal cylinder drive chain 104 is tightened by an idler sprocket 293 that is carried by an arm 294 as shown in Fig. 2.

To facilitate lining up of the conveyor pins 122 a collar 146, fixed on the shaft 112, has a notch 295 which makes one revolution when the pins have advanced one space and the notch is 35 engaged by a pawl 296 to give an audible signal. A gauge (not shown) may be set up in a fixed position in the path of the pins, and when the pawl drops into the notch the pins immediately adjacent the gauge are adjusted so that they both 40 contact the gauge. This squares up the pins in a transverse direction so that the envelopes are advanced with their rear edges parallel with the printing roller. The conveyor chains are then advanced until the pawl again engages the notch 45 after which the next set of pins are adjusted to the gauge. This adjustment also assures that the pins are equally spaced apart along the length of the conveyor chains and that the envelopes reach the printing roller in the same relation.

50 Assuming that the machine is constructed and assembled as described, the operation is as follows: The posts 32-33 and 34-35 are adjusted to the size of the envelopes to be printed. The vertical members 40 and 41 and the vertical feed 55 control member 82 are adjusted relatively to the front of the stack 31. A stack of the envelopes 31 is then placed in position between the posts with their rear edges supported on the tongues or rests 72 and 73 and their front edge portions 60 supported on the withdrawal cylinder 30. If the front faces of the envelopes are to be printed, they are placed face down in the stack but if the rear faces are to be printed, they are placed front face up. The envelopes may be turned to be best accommodated within the press; for example, if open end envelopes are to be printed they are placed with the closure flaps to one side so that the major length of the envelopes are transversely of the press. Also the flaps may be either open or closed. The adjustments to the stack supports are effected by loosening the fastening devices 39, 45 and 84', and shifting the posts and supporting members to their desired position, after which the fastening devices are retightened. 65 The member 82 is then adjusted vertically

through operation of the knurled adjusting screw 88 so as to apply the required pressure of the flexible lip 91 on the withdrawal cylinder to permit proper passage of a single envelope when engaged by the suction nozzles of the withdrawal cylinder later described. The supporting finger 101 is adjusted relatively to the stack so that it lightly engages between envelopes in the stack for cooperation with the resilient facing 83 in supporting weight of the upper portion of the stack.

The guide rails 128 and 129 are adjusted laterally of the crossbar 125 according to the transverse width of the envelopes at the delivery ends thereof while the entrance ends are spaced a greater distance apart to allow free entrance of the envelopes. This adjustment is effected by placing one of the side guides at an angle relatively to the other side guide. The shift arm 246 is adjusted on the shaft 247 so that it swings into position to engage the ends of the printed envelopes, discharged from the printing mechanism. The stop 271 is adjusted on the table to control the extent of displacement of an envelope by the shift arm 246.

It is now assumed that the withdrawal cylinder 30 is connected with a suction pump, and that the motor 3, cylinder 30, feed conveyor, printing unit, and delivery conveyor are all in operation. The printing plate is attached to the printing plate cylinder in proper position by usual methods for example by a "sticky back" material. Another adjustment to be made is to synchronize the conveyor pins with the printing plate cylinder. This is effected through adjustment of the sprocket 144 on the shaft 112 by means of the knurled coupling collar 145.

When the withdrawal cylinder 30 rotates a pair of suction nozzles thereof pass under the lowermost envelope in the stack. The manifold channels supplying this pair of nozzles are then in connection with the nipple 70 and suction hose 71 through the arcuate channel 69 of the valve disc. The suction thereby draws the first or bottom envelope of the stack into contact with the face of the withdrawal roller so that it is carried under the lower ends of the backing members 40 and 41, and under the flexible lip 91. Continuing the advance, the withdrawal cylinder carries the envelope through the arcuate pass 76 and onto the upper edges of the guide tracks 118 and 119 completely reversing the position of the envelope in that the face side is now up. By this time, the suction is cut off by the manifold channel passing the arcuate channel 64 of the valve disc which leaves the envelope free to be picked up by the pins 122 on the chain belts 115 and 116. Contact of the pressure or transfer rolls 135 with the cylinder 30 aid in straightening out the envelope for removal along the conveyor chains. The envelopes are then pushed along the guide rails with the ends being guided by the side guides 128 and 129. As the envelopes are moved along the rails they are being shifted sidewise by the canted guide rail into side contact with the straight-away guide rail so that when the envelopes reach the delivery ends they are in registry with the printing plate on the printing plate cylinder. The conveyor chains carry the envelopes under the brush or retarding element 211 which assures that the rear edges of the envelopes are held against the pins. The envelopes continue their advance under the contact arm 183 and into the printing unit. If an envelope fails to be delivered, the rotating cam 187 makes con-

tact with the switch 186 to effect energization of the electric magnet 185 which manipulates the rod 191 to release the latch 194 from engagement to the arm 197, thereby permitting the impression cylinder 14 to drop from contact with the printing plate cylinder 13 so that an offset is not effected in the impression cylinder. In case the envelopes should begin to bunch up under the top guides 155, the center rod 167 is lifted thereby to actuate switch 175 to stop operation of the machine. The bunched-up envelopes are then readily removed by lifting the frame 158. After clearing out the envelopes, the frame is lowered and the machine is again started. When the envelope reaches the end of the conveyor chains the pins 122 push it into the path between the gripping rollers 209 and 210 and as the gripping rollers have a faster peripheral speed they carry the envelope away from the conveyor pins and feed it under the guides 215 to the pass between the printing plate and impression cylinders. The gripping rollers retain their grip on the envelope while it is passing under the printing plate cylinder and until it has been gripped by the rollers 217. When the rollers 217 have a grip on the envelope the trailing edge has passed the rear gripping rollers, with the result that the envelope is always held in register while being printed. Therefore, the envelope cannot slip out of registration while passing between the printing plate and impression cylinders; consequently the printing is applied in the required position and in proper relation with the sides and ends of the envelope.

After the envelope is released by the rollers 217 and before being contacted by the wheels 238 and 239 they drop in flight onto the delivery table. If the envelope is for example the last envelope of a given count, the arm 246 comes into play and shifts the envelope while in flight against the stop 271.

The envelopes after dropping onto the table are carried therealong by the upper surface 236 and 237 of the belts to the stop rests 280 from where they are removed by the person operating the press.

It is obvious that since the first of the envelopes in the stack is maintained in contact with the peripheral face of the withdrawal cylinder, the envelopes are engaged by the suction nozzles and withdrawn thereby, so that thickness of the envelopes is not a factor. Also the flaps form no function in the withdrawal so that the envelopes may be fed with the flaps opened or closed and the possibility of a stuck flap has no bearing upon the feed.

It is also obvious that in the case of jammed envelopes on the feeding conveyors, the press is stopped automatically and the envelopes are readily removed by merely lifting of the guide frames and cleaning out the disarranged envelopes. It is also apparent that failure of an envelope to feed stops the printing operation since the impression plate cylinder is automatically dropped from out of printing relation with the printing plate cylinder.

The transition of the envelopes from influence of the chain pins 122 to the feeding or gripping rollers is most important because the surface speed of these rollers speeds up the envelopes at this point and prevents their rear edges from being "bumped" or deformed by the sweep of the conveyor pins 122 as they pass around the sprockets 113 and 114. The feed rollers also as-

sure accurate placement of the printing on the envelopes.

The press constructed and operated as described is characterized by its small size, ease of make-ready, simplicity in operation, positive feed, accuracy of registration, and speed of printing so that envelopes and the like may be economically printed to suit a customer's needs.

I claim:

1. In a printing press, a printing mechanism, means for supporting a stack of workpieces, a pair of endless conveyor chains, shafts and sprockets supporting said chains, a withdrawal cylinder below the stack supporting means and above the endless conveyor chains for withdrawing workpieces from the stack supporting means and carrying the workpieces into an inverted position on the conveyor chains, pins on the conveyor chains for engaging edges of the workpieces and advancing the workpieces to the printing mechanism, guides extending along the outer sides of the conveyor chains for guiding side edges of the workpieces while being advanced to the printing mechanism, means for holding the workpieces in contact with the conveyor chains, means for actuating the conveyor chains, means including a switch on said frame for stopping actuation of the conveyor chain actuating means, and an operative connection between said holding means and said switch for opening of the switch to stop the conveyor chain actuating means in the event stoppage of workpieces should occur under said holding means.

2. In a printing press, a printing mechanism, means for supporting a stack of workpieces, a pair of endless conveyor chains, shafts and sprockets supporting said chains, a withdrawal cylinder below the stack supporting means and above the endless conveyor chains for withdrawing workpieces from the stack supporting means and carrying the workpieces into an inverted position on the conveyor chains, pins on the conveyor chains for engaging edges of the workpieces and advancing the workpieces to the printing mechanism, guides extending along outer sides of the conveyor chains for guiding side edges of the workpieces while being advanced to the printing mechanism, a frame, longitudinal bars carried by the frame for holding the workpieces in contact with the conveyor chains, means for actuating the conveyor chains, means including a switch on said frame for stopping actuation of the press, means movably supporting one of said longitudinal bars on the frame, an operative connection between the movable bar and said switch for opening of the switch to stop the motor in the event stoppage of workpieces should occur under said movable bar, and means for pivotally supporting the frame for movement from over the conveyor chains to an out of the way position to facilitate movement of the jammed workpieces.

3. A printing press including a printing mechanism having printing plate cylinder and an impression cylinder, means for supporting a stack of workpieces, a feed conveyor for moving workpieces in successive order to the printing mechanism, a withdrawal cylinder, means rotatably supporting the withdrawal cylinder below the stack supporting means and above the feed conveyor for withdrawing workpieces individually from the stack supporting means and carrying the workpieces into an inverted position on the feed conveyor, means for actuating the feed conveyor and printing plate cylinder in synchro-

nism to position arrival of the workpieces relatively to the plate cylinder, gripping rollers between the feed conveyor and printing plate and impression cylinders for receiving the workpieces from the feed conveyor and passing the workpieces between the printing plate and impression cylinders, and means for operating the gripping rollers at a higher peripheral speed than the speed of the feed conveyor.

4. A printing press including a printing mechanism, having a printing plate cylinder and an impression cylinder, means for supporting a stack of envelopes, a feed conveyor for moving the envelopes in successive order to the printing mechanism, said plate cylinder having a printing contact point in plane with the feed conveyor, means for actuating the feed conveyor, gripping rollers having fixed axes and located between the feed conveyor and the printing plate and impression cylinders for gripping the respective front and back faces of the envelopes as they are presented by the feed conveyor and until an envelope gripped thereby is passing the contact printing point between the printing plate and impression cylinders, and means for operating the gripping rollers at a higher surface speed than the speed of the feed conveyor to clear a gripped envelope from further contact with the conveyor.

5. A printing press including a printing mechanism, having a printing plate cylinder and an impression cylinder, means for supporting a stack of envelopes, a feed conveyor for moving envelopes in successive order to the printing mechanism, means for actuating the feed conveyor, gripping rollers between the feed conveyor and the printing plate and impression cylinders for receiving the envelopes from the feed conveyor and passing the envelopes between the printing plate and impression cylinders, gripping rollers cooperating with the impression cylinder to grip the envelopes while the envelopes are passing the printing plate cylinder and means for operating the first named gripping rollers at a higher surface speed than the speed of the feed conveyor.

6. A printing press including a printing mechanism, having a printing plate cylinder and an impression cylinder, means for supporting a stack of envelopes, a feed conveyor for moving envelopes in successive order to the printing mechanism, a withdrawal cylinder, means rotatably supporting the withdrawal cylinder below the stack supporting means and above the feed conveyor for withdrawing envelopes individually from the stack supporting means and carrying the envelopes into an inverted position on the feed conveyor, means for actuating the feed conveyor and printing plate cylinder in synchronism, gripping rollers between the feed conveyor and printing plate and impression cylinders for receiving the envelopes from the feed conveyor, said gripping rollers being located relatively to the contact printing point of the printing and impression cylinders to maintain grip on the envelope while the envelope is progressing through said printing point, and means for operating the gripping rollers at a higher surface speed than the speed of the feed conveyor to clear the envelopes from further contact by the conveyor.

7. A printing press including a printing mechanism, having a printing plate cylinder and an impression cylinder, means for supporting a stack of envelopes in face down position, a feed conveyor for moving envelopes in successive order to the printing mechanism in substantial align-

ment with the printing point between said cylinders, a withdrawal cylinder, means rotatably supporting the withdrawal cylinder below the stack supporting means and in position to contact face sides of the envelopes for withdrawing envelopes individually from the stack supporting means and carrying the envelopes into a face up position on the feed conveyor, means for actuating the feed conveyor and printing plate cylinder in synchronism, gripping rollers between the feed conveyor and printing plate and impression cylinders for engaging the envelopes therebetween and passing the envelopes through the printing point between the printing plate and impression cylinders while the envelope being printed is gripped thereby, gripping rollers cooperating with the impression cylinder to continue grip on the envelope while the envelopes are passing said printing point, and means for operating the gripping rollers at a higher surface speed than the speed of the feed conveyor to clear the envelopes from further contact by the feed conveyor.

8. A printing press including a printing mechanism, having a printing plate cylinder and an impression cylinder, means for supporting a stack of envelopes in face down position, a feed conveyor for moving envelopes in successive order and in face up position to the printing mechanism, a withdrawal cylinder for contacting the face side of the envelopes, means rotatably supporting the withdrawal cylinder below the stack supporting means and above the feed conveyor for withdrawing the workpieces individually from the stack supporting means and carrying the workpieces into said face up position on the feed conveyor, means for actuating the feed conveyor and withdrawal cylinder in synchronism, gripping rollers between the feed conveyor and the printing plate and impression cylinders for receiving the envelopes from the feed conveyor and passing the envelopes between the printing plate and impression cylinders, gripping rollers cooperating with the impression cylinder to grip the envelopes while the envelopes are passing the printing plate cylinder, means for operating the gripping rollers at a higher surface speed than the speed of the feed conveyor to clear the envelopes from further contact by the feed conveyor, a delivery table for receiving the printed envelopes discharged by the second named gripping rollers, endless conveyor means operative along the table to move the printed envelopes, and means for actuating the endless conveyor means at a slower speed than the peripheral speed of said second named gripping rollers for lapping of the envelopes on said table.

9. A printing press including a printing mechanism, having a printing plate cylinder and an impression cylinder, a feed conveyor for moving workpieces in successive order to the printing mechanism, means for actuating the feed conveyor, gripping rollers between the feed conveyor and the printing plate and impression cylinders for receiving the workpieces from the feed conveyor and passing the workpieces between the printing plate and impression cylinders, gripping rollers cooperating with the impression cylinder to grip the workpieces while the workpieces are passing the printing plate cylinder, means for operating the gripping rollers at a higher surface speed than the speed of the feed conveyor, a delivery table for receiving the printed workpieces discharged by the second named gripping rollers, endless conveyor means extending along the table to move the printed workpieces, means

for actuating the endless conveyor means at a slower speed than the peripheral speed of the gripping rollers, and means between the second named gripping rollers and the endless conveyor means for laterally deflecting selected workpieces.

5 10. In an apparatus for feeding envelopes to a printing unit having a shiftable impression cylinder, a supporting frame, a conveyor on the supporting frame for feeding the envelopes to the printing unit, a contact member supported by the frame in contact with the envelopes carried by the conveyor, a cam actuated switch in series with the contact member and rotatable in timed relation with the conveyor to close circuit through the contact member in the absence of an envelope on the conveyor, means for shifting the impression cylinder, and means responsive to closure of said circuit through the contact member for actuating said impression cylinder shifting means.

15 11. An apparatus for feeding workpieces to a printing unit including a conveyor, a supporting frame, means on the supporting frame for carrying a stack of workpieces to be printed, means for effecting feed of the workpieces from the stack and depositing the workpieces on the conveyor, pins on the conveyor for engaging rear edges of the workpieces to move said workpieces with the conveyor, means for retarding workpieces to assure contact by said edge engaging means, and means for operating the workpiece feeding means and conveyor including means for advancing and retarding movement of the conveyor to synchronize position of the workpieces relatively to printing position of the workpieces in said printing unit.

20 25 30 35 12. In a printing press including a supporting frame, rests carried by the supporting frame for carrying a stack of envelopes to be printed, a withdrawal cylinder having suction ports, means rotatably supporting the withdrawal cylinder on the frame in position below said carrying means, stack backing members carried by the frame and having lower ends spaced above the withdrawal cylinder to provide passageways for the envelopes, a resilient member carried by the frame intermediate the stack backing members and having a terminal contacting the withdrawal cylinder and under which the envelopes are passed, and means for establishing suction through said ports for effecting withdrawal of the lowermost envelopes from the stack.

40 45 50 55 13. In a printing press including a supporting frame, rest means carried by the supporting frame for carrying a stack of envelopes to be printed, a withdrawal cylinder having suction ports, means rotatably supporting the withdrawal cylinder on the frame in position below said rest means, stack backing members carried by the frame and having lower ends spaced above the withdrawal cylinder to provide a passageway for the envelopes, a resilient member carried by the frame intermediate the stack backing members and having a terminal contacting the withdrawal cylinder and under which the envelopes are passed, means for establishing suction through said ports for effecting withdrawal of the lowermost envelopes from the stack, and means for adjusting pressure of the terminal on the withdrawal cylinder.

60 65 70 75 14. In a printing press, a printing plate cylinder adapted for carrying a printing plate, an impression cylinder cooperating with the printing plate cylinder in forming an impression on a workpiece passed between said cylinders, means for actuating said cylinders with the surface of

the printing plate operating at the same surface speed as the impression cylinder, feed rollers at one side of the cylinders for gripping the workpiece and feeding the workpiece between said cylinders, means for operating the feed rollers at the same surface speed as the impression cylinder to feed the workpiece at the speed of the printing plate, and gripping rollers at the opposite side of said cylinders and having contact with the impression cylinder for maintaining registry of the workpiece after release by the feed rollers.

15. An apparatus for feeding envelopes from a means for supporting envelopes in stacked relation to a printing mechanism, said feeding apparatus including a pair of laterally spaced parallel rails extending from below said stack supporting means to the printing mechanism and having upper edges forming supports along which the envelopes are adapted to slide, side guides spaced outwardly from the rails and having flange portions substantially in plane with said edges of the rails to cooperate therewith in supporting the envelopes and having vertical flange portions for engaging ends of the envelopes to establish transverse registry with the printing mechanism as the envelopes are moved along the rails, shafts extending transversely below the respective opposite ends of the rails, sprockets on the shafts, endless chains operating over the sprockets with upper runs thereof extending along the rails and spaced below said upper edges of the rails to be out of contact with the envelopes, pins projecting from the chains and adapted to project above the edges of the rails as the chains carry them along the rails in pushing contact with rear edges of the envelopes, retarding means having support between the rails to make contact with the envelopes and assure said contact by the pins, a withdrawal cylinder having a peripheral face provided with a port through which a vacuum is drawn and released, means supporting the withdrawal cylinder above the

rails and with the peripheral face in contact with the first of said envelopes in the stack to effect withdrawal of said envelope downwardly and forwardly under the withdrawal cylinder, a transfer wheel having support intermediate the rails and in position to cooperate with the peripheral face of the withdrawal cylinder to feed said envelope therebetween and onto the rails substantially upon release of the vacuum, top guides having support above the rails and in position to retain the envelopes in sliding contact with said edges of the rails and the rear edges of said envelopes from lifting upwardly over the pins when the envelopes are engaged by said retarding means, and feed rollers between the rails and the printing mechanism to continue feed of the envelopes into the printing mechanism.

16. An apparatus as described in claim 15 including a frame carrying the top guides and the retarding means, and means for pivotally supporting the frame relative to the rail and side guides.

ROSS E. SKOW.
